DEVICE FOR PARALLELIZING FIBERS IN
SLIVER OR ROVING DURING DRAFTINGBenjamin B. Cravens, Pawtucket, R. I., assignor,
by mesne assignments, to Whitin Machine
Works, a corporation of Massachusetts

Application September 8, 1949, Serial No. 114,562

7 Claims. (CL. 19—130)

1

My invention relates to a new and improved method and apparatus for drafting natural or synthetic textile fibers in strand form, such as sliver, roving, and the like, in drawing mechanisms of drawing frames, roving frames, spinning frames, and similar textile machines.

Many different forms of condensing devices have been proposed heretofore for reducing sliver, roving, and the like to greater compactness in textile drawing operations. The art has, heretofore, developed compacting or condensing devices in the form of a funnel or trumpet, either as a closed tube or with an open slot or passageway at the top. Devices of this character in use at the present time usually are attached to a traverse rod for reciprocating movement transversely of the path of fiber travel and positioned a substantial distance clear of the nip formed by the drafting members which immediately follow the condenser thereby relinquishing control of the sliver, roving or fibrous strand as soon as it clears the outlet of the funnel or trumpet with consequent loss of the fiber condensing effect due to the tendency of the fibers to splay and swell out in the free span between the outlet of the condenser and the nip of the fiber-pulling members following the condenser.

The whole purpose of drafting, as performed in drawing frames, roving frames, spinning frames, and similar textile machines, is to effect a combination of separating lengthwise, or drawing apart, the fibers of cotton, wool, rayon, or other fibrous textile weaving material, into a thinner strand and parallelizing the fibers in the strand of sliver or roving. As above stated, present forms of condensing devices tend to defeat the basic principle of parallelism by turning inwardly or lapping the fibers over each other. Obviously, lines of fiber travel which cross each other cannot be parallel to each other. It is believed that greater draft, of more uniform consistency, can be obtained by eliminating the intermixing or overlapping of fibers from the edges of the sliver being drawn toward and over the inner fibers of the strand or sliver, through the use of improved design of the condensing devices and the imposing of new means of controlling lines of fiber travel during the drafting process.

In its broad aspects my invention relates to the manufacture of yarn from sliver or roving by means of a novel method and apparatus wherein the fibers of the sliver or roving during a drawing operation are caused to travel between two positions, one being a position at which the array or strand of sliver or roving is substantially

flat in transverse cross-section and a second position at which the strand is in a condensed and compacted form, the fibers of the strand being caused to travel during the drawing operation along courses of equal length in passing from the first position to the point where they are condensed and compacted and at which they arrive in converging lines of flow under tension; the arrangement being such that the distance 5 traveled, and consequently the tension, being substantially uniform for all lines of travel or courses made by the individual fibers throughout the width of the sliver or roving in passing between the two positions; and further characterized in that the sliver or roving is put in a compacted condition solely at the second position. My invention also is directed to the provision of a mechanism for drawing sliver or roving for making yarn and includes in its organization 10 a pair of opposed holding rolls receiving a strand of sliver or roving and between which the strand passes in a compressed flattened form or ribbon-like strip, a pair of opposed rotatable pulling members or rolls cooperating to provide 15 a line of nip therebetween and arranged to draw those fibers of this strip whose front ends are gripped by the pulling members and whose tail ends are subjected to a retarding tension by adjacent other fibers held by the holding rolls, and also to propel the sliver or roving forwardly and 20 away from the holding rolls under tension as the drawing operation is performed by the pulling members, and a novel condensing device located in the drafting zone between said pairs 25 of holding rolls and pulling members, and by means of which device the drawn fibers are displaced in opposite directions for an amount such that they are caused to travel in courses of equal length to straighten out the fibers so that they 30 will pass into a condensing and compacting region in a more nearly parallel relationship to each other before entering the bite of the pulling members.

This condensing device comprises a supporting body which includes a fiber condensing and compacting member having a restricting discharge aperture the delivery end of which is to be placed close to the nip of the pulling members when the device is in its normal working position, 45 a convex fiber spreading and distributing member situated in advance of said fiber compacting member, and a convex member positioned ahead of said fiber spreading and distributing member and arranged to tension and guide the fibers 50 thereto after the strand has passed the bite of

the holding rolls in advancing to the pulling members. The convex members engage in succession opposite sides of the flattened strip of sliver or roving in its regular travel to the compacting member from the holding rolls, the fibers being influenced by the convexity of both convex members in passing thereover and caused thereby to travel in courses of equal length to the compacting member. Thus, the drawn fibers are deflected first downwardly and then upwardly by the convex members, the fibers situated near the mid-portion of the main body of the strip being caused to follow a course having the greatest deflection from a straight line while those close to the side edges of the strip make a course having the least deflection in passing under and over the convex members as the courses of the drawn fibers are caused to converge to the compacting member. In addition, my invention further contemplates a condensing device which is so fashioned that it will create a slight tension in the strand of sliver or roving, independent of the standard draft of the machine, starting as the sliver or roving passes into the entrance area of my improved condensing device. The friction thus imposed will press the fibers against or toward successive reverse bends presented by the condenser transversely of the sliver or roving. In practice, the condenser is provided with two oppositely convex curved bending members arranged transversely of the strand of sliver or roving to operate successively thereon to bend it in opposite transverse directions as the sliver or roving passes under and over said curved surfaces, the fiber engaging surface of each of said bending members being curved convexedly both laterally and longitudinally. Consequently, natural lines of force will cause the fibers to attempt to retain their original lateral relationship in passing through this new condenser rather than to gather or to fold over each other, which latter result is obtained in use of present funnel types of condensing devices.

Another feature of my invention contemplates the reduction to a minimum of the length of travel of the fibers through the discharge orifice of the condenser to an extent whereby the fibers are not able to cross each other within the orifice.

A further feature of my invention contemplates a notched compacting member forming the exit end and the fiber discharge orifice of the condenser device for condensing the sliver or roving following its passage across the curved bending members; the width and depth of said orifice being restricted to the natural space requirements of the strand of sliver or roving whereby a more completely parallel positioning of the fibers will be accomplished.

Parallelism during condensation of the fibers is effected in my improved condenser design by drawing all fibers through the same linear distance to the discharge orifice of the condenser device. The convex bending members interposed between the notched compacting member and the holding members or rolls displace the portions of the strands of sliver or roving in opposite directions for an amount such that the distances along the converging lines or courses of travel of the drafted fibers between the fiber holding members or rolls and the compacting member of the condenser are uniform and equal; consequently the tension is substantially uniform throughout the width of the sliver or roving. This notched orifice should be positioned to lie as close as physically possible to the line of nip

of the pair of opposed pulling members, such as drawing rolls, belts or aprons, when operating on sliver or roving and between which the fibers must pass to the next draft stage, and yet avoid clogging of the machine. Consequently, the fibers are not given an opportunity to curl or deflect from the intended line of travel. This "free" distance preferably should be shorter than the length of the individual fibers (average) and the radius of their natural curling arc.

By the elimination of any trumpet action or gathering together of the fibers within the condenser unit ahead of the orifice, the tendency of the fibers to intermingle and be forced out of parallel position is removed. The width of my condenser should be made wider than the lines of force impelling the travel of the sliver at all points excepting at the discharge orifice itself.

By deflecting the strand of sliver or roving under and over the opposed convex curved surfaces of my bending members which are so placed that the intersecting line of the arc is essentially parallel to the lines of contact of the rolls limiting the draft area, the fibers will be restrained from bunching and folding or crossing one another during the condensing operation. The radius of curvature of the convex curved bending surfaces is calculated so that the natural friction of the fibers will balance with the tendency to outward slippage of the fibers as they pass over the curvature of these arcs, thus placing and holding each of the fibers in a natural line of travel from the point of leaving the preceding draft roll and the point of entry in the orifice of the condenser. The radii of the various arcs might vary with different draft ratios and weights of sliver employed and the width of the strand as it enters the area in which my invention is used.

The overall length of the condenser preferably should be shorter than the average length of the fibers being drafted in order to eliminate any tendency of the fibers to draft to any material extent within the condenser in excess of the ratio of draft in the "draft area" into which the condenser is inserted.

The amount of deflection of the sliver or roving passing through the condenser is such that excessive friction, which might separate the fibers, or break the continuity of sliver, is eliminated.

The arcs should have such radii that the theoretical travel distance through the condenser will be constant for any given course of travel in the draft area, within the normal working limits of the width of sliver or roving and range of "traveler" motion.

It is accordingly one object of my invention to control sliver or roving in the process of drafting in such a fashion as to cause the individual fibers to travel through equal linear distances as the strand of fibers is being attenuated in a drafting mechanism.

Another object of my invention is to provide an improved condensing device which can be positioned close to the nip of the fiber pulling members and so arranged as to cause the relationship of fibers to be maintained during the condensing process in such manner that there will be no tendency for fibers to "climb" over each other or to fold the strand in any way.

Other objects and advantages of my invention will be more apparent by reference to the following detailed description of the several embodiments of my apparatus and method chosen for

the purpose of illustration in the accompanying drawings, and the novel features of my invention will be particularly pointed out in the appended claims.

In the drawings:

Fig. 1 is a diagrammatic view, in elevation, showing one embodiment of my improved condenser device in place between adjoining sets of drawing rolls which form a draft stage or zone in a textile drawing mechanism;

Fig. 2 is an enlarged perspective view of the condenser device shown in Fig. 1 and as viewed facing the discharge orifice and looking rearwardly down into the condenser device;

Fig. 3 is a greatly enlarged perspective view of the condenser shown in Fig. 2 as viewed from above and looking down into the condenser device from a side thereof;

Fig. 4 is an enlarged plan view of a modified form of condenser device similar to that shown in Fig. 2 but with side restricting walls on the middle transverse bend member;

Fig. 5 is an enlarged transverse section taken substantially on the line 5—5 of Fig. 4;

Fig. 6 is an enlarged front elevation of another modified form of condenser device similar to that of Fig. 2 but with a side opening in the outlet for threading purposes;

Fig. 7 is a diagrammatic view, in elevation, illustrating one embodiment of my improved method and showing one of my improved condenser devices in a drawing mechanism for performing the method of my invention to cause the individual fibers to pass through equal linear distances as the strand of sliver or roving is being condensed in a draft zone; and

Fig. 8 is a diagrammatic top plan view illustrating the condensing action of my improved condenser.

Referring to the drawings, Fig. 1 shows spaced pairs or sets of upper and lower cooperating rolls 10, 11 and 12, 13, respectively which also are respectively the front and rear rolls of a draft stage or zone of a drawing mechanism associated with either a roving frame or a spinning frame. Thus, the pairs of rolls 10, 11 and 12, 13 may provide either a draft stage of great draft for the fibers being processed or they may form merely a tension draft zone in the drawing mechanism of such textile machines. If desired, the fiber drafting organization provided by the rolls 10, 11, 12 and 13 may be utilized in combination with a break draft stage or zone which as usual precedes one or more greater draft stages or zones in drawing mechanisms of this class, in which instance, the pair of back or feed rolls 14 and 15 and the rolls 12 and 13 provide a break draft zone as illustrated in Fig. 7.

The top rolls 10, 12 and 14 are of conventional construction each comprising a relatively short roll having fiber engaging portions covered with leather or other covering material in common use.

The top rolls of each set are pressed against their associated lower rolls by means of suitable pressure weighting mechanism, as is well known practice in the art, and not here illustrated, whereby the array or strand of fibers S passing between the pairs of drafting rolls will be firmly gripped thereby and carried forward in succession between each pair of rolls and the desired drafting effected if the settings of the pairs of drafting rolls are properly adjusted and the relative surface velocities and speeds of the rolls is provided.

The bottom rolls 11, 13 and 15 are positively driven and of usual construction as commonly used in the art in that each may consist of a longitudinally fluted metallic roll of considerable length made up of a number of short fluted sections joined together end-to-end by suitable coupling means (not shown). The construction and arrangement of these rolls is conventional and well known in the art so that further description 10 will not be given except to state that the bottom rolls are journaled for rotation in suitable bearing members (not shown) which are arranged for relative adjustment and may be set appropriate for the staple of the fibers being drafted. In practice, the bottom rolls may or may not be caused to be rotated at increased speeds to provide faster surface velocities to the succeeding rolls engaging the fibrous strand S of roving or sliver in its forward travel from the pairs of rolls 14, 15; 12, 13 and 10, 11 respectively whereby it is the accepted practice in the art to so operate and regulate the several successive sets of rolls that they will rotate with the proper peripheral velocities to effect the required total draft of the strand of sliver or roving S passing between them during its forward travel through the successive zones. Thus, in the particular arrangement illustrated in Fig. 7 the pair of back rolls or feed rolls 14 and 15 respectively, draw the fibrous strand S from a can or a spool (not shown) or other suitable source of supply, and feed it forward to the pair of intermediate draft rolls 12 and 13. In front of these are shown the front or delivery rolls 10 and 11. In practice, the fibrous strand S may be drawn through a rear trumpet (not shown) before entering the bite or nip of the back rolls 14 and 15, as is a usual practice in the art.

Thus, in accordance with the foregoing description, the three consecutive pairs or sets of rolls shown in Fig. 7, of which the Fig. 1 representation may comprise a portion thereof, there will be provided two consecutive draft stages or zones, the first being a "break" draft area between rolls 14, 15 and 12, 13, and the second being an area or stage of greater draft, the "break" draft being of the order of 1.25 or upward. The second draft zone is between the pair of rolls 12, 13 and the next succeeding pair 10, 11.

Between the cooperating pairs of rolls 10, 11 and the rolls 12, 13 is arranged my novel and improved fiber reducing device or condenser 16. If desired, the drawing mechanism may include a succession of additional pairs or sets of draft rolls to supplement the roll arrangement shown in Fig. 7 so as to add draft stages or zones and to provide either a four-line or a five-line drawing system in which instances similar condensers or reducers of appropriate size may be placed between one or more of the succeeding draft stages. The specific structure of my condenser or reducer device 16 now will be described in detail as the specification proceeds.

It will be understood that in connection with the following description the terms employed in so describing my condenser or reducer device and in claiming it, such terms as "front," "middle," "rear," "forward," "upper," "rearwardly," "below," "elevated," and "downwardly" are to be considered as relative rather than limiting as the device obviously could be used in various positions in a drawing mechanism.

Referring to Figs. 1, 2, 3 and 7, the reducer or condenser device 16 comprises a base portion 17 which is suitably secured to an angle bracket

18 both legs of which are bifurcated as shown in Figs. 2 and 6 and secured to a traverse bar 19 (see Figs. 1 and 7) by which it is positioned and supported in operative relation with respect to two pairs or sets of draft rolls in the drawing mechanism of the machine with which it is used. The overall length of the condenser preferably should be made such that discharge of the fibers will be as close as possible to the nip of the succeeding pair of rolls while entrance of the fibers can be as close as possible to the pair of rolls immediately preceding the condenser. This overall length of the condenser, however, should be shorter than the "rated" length of fibers being drafted.

The base 17 incorporates a rearwardly disposed transversely extending curved bend or arm member 20, a middle or intermediate elevated transversely extending curved bend or expander member 21, and a forward extension in the form of an upturned notched compacting member 22. The underside of the back bend or arm 20 is curved convexly both longitudinally and transversely as shown by the convex arc 23 in Fig. 2 and the convex arc 24 in Fig. 1 respectively, and is spaced above and extends transversely of the base portion 17.

The middle bend or expander member 21 is of special formation, here shown in Figs. 1, 2 and 3 as being of relatively sharp triangular section longitudinally of the base and having its peak or transverse ridge 25 on a convex curved arc extending transversely of the base portion 17. The rearward side of the expander member 21 is curved laterally on its upper face 26 on a convex surface formation to the ridge 25 and is slantingly directed downwardly therefrom and terminates partially beneath the back bend or arm 20. The forward side of the expander member 21 also is curved laterally on its upper face 27 on a convex surface formation to the ridge 25 and is slantingly directed toward the rear portion of the upturned compacting member 22 and at its forward end being on a concave curve and merging into the upper forward surface portion of the compacting member 22. In its front upper portion the compacting member 22 is on a convex curve and hence the upper surface from the front end of the compacting member 22 to the ridge 25 as a whole represents a compound curved surface. Formed in the compacting member 22 is a downwardly inclined central discharge aperture 28 which extends therethrough and is shown at 29 as being of partially circular formation the curved sides of which join at their upper ends with the sides of a relatively deep sharp notch 30 which forms the compacting orifice of the member 22.

The condenser structure above described thus will cause the initial relationship of fibers to be maintained during the condensing process so that there will be no tendency for fibers to "climb" over each other or to fold the web in any way, i. e. the fiber which leaves the preceding rollers at the left outer edge of the web will still be at the left outer surface of the condensed web, the only dislocation will be the unavoidable "stacking" of fibers requisite to passage through a narrower space. Since contact of the fibers within the central aperture 28 and the notch 30 must be so short that the natural tendency of the fibers to climb over each other in passage through this restricted area will be reduced to a minimum, the width of aperture 28 and the notch 30 should be restricted to the natural space

requirements of the strand of sliver or roving. Also, the notch 30 is made narrower than the transverse length of the convex bending members whereby the fibers of the sliver or roving are caused to travel along converging lines.

The radii of various arcs and lengths of my condenser device may vary with different drafts, weights of sliver or roving, the length of the draft zone and width of strand being processed. All sharp corners, either inside or outside, should be eliminated. The surfaces which contact the sliver or roving preferably should be as short as practical in relation to the longitudinal travel of sliver or roving through the condenser. During passage of fibrous strand through my condenser device the edges of the sliver or roving should be practically undisturbed in line of travel from the pair of fiber engaging rolls immediately preceding the condenser to the discharge orifice of the condenser. The distance traveled by the center fibers of the strand is determined by control of the size and shape of the notch 30, the curvature of the upper surface of convex arc 25 of the middle bend, and the curvature of the lower surface of convex arc 23 of the back bend 20. Friction in passage of fibers through this condenser is reduced to the minimum required to obtain sufficient dislocation of line of fiber travel to accomplish passage of fibers through the same distance within the zone, whether the fiber leaves the preceding rolls at the outside or inside of the web, without causing the fibers to "slide" sidewise on the convex curved surfaces of the condenser bends.

In practice, the convexed curved transverse bending surfaces of the bending members 20 and 21 of the condenser should be made sufficiently wide so that fibers at the outer edges of the sliver or roving will not touch any side restriction until they actually enter the discharge aperture 28 and the notch 30, and at that point the lines of travel of the fibers will be in controlled relationship to "vertical" pressure instead of "side" pressure and will be devoid of trumpet action by the condenser.

In Figs. 4 and 5 I have shown a modified form of reducer device or condenser which differs from the form of construction illustrated in Figs. 1, 2 and 3 in that the ridge or expander member 21 is provided at its sides with upstanding guide walls 31 and 32, the inner faces of which are convexedly curved longitudinally of the device. In a drawing operation there is frequently experienced a tendency for certain fibers at the edge of a moving strand of sliver or roving to fly outwardly away from the strand and become disassociated and lost; consequently, the convex guide walls 31 and 32 provided in this modified form of device will deflect these disassociating fibers back toward the strand, thus preventing the loss of such fibers. The guide walls 31 and 32 are here illustrated therefore as an adjunct to the device of my invention and they have no direct bearing on the principal functions thereof.

In Fig. 6 I have shown another modified form of reducer device or condenser in which the outlet opening in the forward compacting member 22 is slotted at one side as at 33 to facilitate threading of the strand of sliver or roving into the aperture 28 and the notch 30.

Fig. 8 is a diagrammatic presentation of the principle employed in computing the curvature and radii of the convex arcs 23 and 25 of the respective convexedly curved bending members 20 and 21 respectively (see Figs. 1 and 2). The

lines AA' and BB' represent the centers of contact of the fiber holding and pulling rolls, respectively, of the draft zone illustrated, while the lines CC and DD illustrate the actual nip lines of the respective rolls. Lines 20-20 and 21-21 in this figure represent the center lines of the back bend 20 and the middle bend 21 respectively of the condenser device 16. The distance between line 20-20 and point 30 which indicates the compacting notch of the device represents the effective length of the device. The line EE' represents the natural distance from the point where the outer edge of the strand of sliver or roving is discharged from preceding rolls to the point of compaction. The line EF represents the natural center of the strand of sliver or roving. Line EG represents any other line or distance between EE' and EF, here illustrated midway of the distance between the center and outer edges of the strand. Convex arcs 23 and 25 have radii so computed that the points of intersection with line EE' will not deflect the strand and the sum of the converse altitudes of the arcs, from lines 20-20 and 21-21, respectively, will equal the amount of vertical displacement of this strand required to increase the distance along line EF sufficiently to equal the length of line EE'.

Thus, the vertical displacement along the line EF will be represented by the converse altitudes K and L of the arcs 25 and 23 respectively. Similarly, the vertical displacement along the line EG will be represented by the converse altitudes M and N of the arcs 25 and 23 respectively. Therefore, the length of line

$$EE' = EM' + M'N' + N'G = EK' + K'L' + L'F$$

What I claim is:

1. A condenser device for sliver or roving comprising a support and two oppositely convex curved bending members arranged transversely of the sliver or roving and bending it in opposite transverse directions as the sliver or roving passes under and over the curved surfaces of said bending members, and a notched compacting member forming the exit end of the condenser device for condensing the sliver or roving following its passage across said curved bending members.

2. A condenser device for sliver or roving comprising a support and two oppositely convex curved bending members arranged transversely of the sliver or roving and bending it in opposite transverse directions as the sliver or roving passes under and over the curved surfaces of said bending members, and a compacting member having a notch therein forming the exit end of the condenser device, said notch being narrower than the transverse length of said curved bending members whereby the fibers of the sliver or roving are caused to travel along converging lines.

3. A condenser device for sliver or roving comprising a support and two oppositely convex curved bending members arranged transversely of the sliver or roving and bending it in opposite transverse directions as the sliver or roving passes under and over the curved surfaces of said bending members, and a compacting member having a notch therein forming the exit end of the condenser device, the underside of one of said bending members being convexedly curved both transversely and longitudinally, the upper surface of the other of said bending members being convexedly curved transversely and in its longitudinal extent rising upwardly to a peak forwardly from the back of the condenser and thence sloping sharply downwardly and forwardly from

said peak to merge with the upper side of said compacting member to define therewith a compound curved upper surface.

4. In a mechanism for drawing textile sliver or roving, the combination of a pair of opposed rotatable holding rolls receiving a strand of sliver or roving and through which it passes in a compressed flattened condition, a pair of opposed rotatable pulling members cooperating with each other to provide a line of nip therebetween and arranged to turn together at a peripheral speed greater than that of the holding rolls so as to draft and attenuate the strand as well as to propel it forwardly and away from said holding rolls under tension, and a device for condensing and compacting the fibers of the strand and located in the drafting zone between said pairs of holding rolls and pulling members, said device comprising a fiber condensing and compacting member having a restricted discharge aperture the delivery end of which is positioned close to the line of nip of said pulling members, and a plurality of convex curved members situated ahead of said fiber condensing and compacting member and between it and the holding rolls, the curved surfaces of said convex members being disposed transversely of the strand so as to engage in succession opposite sides of the moving strand and bend it in opposite transverse directions as the strand is guided over said convex members for an amount such that the drawn fibers are caused by the convexity of said convex members to travel along courses of equal length in passing from the holding rolls to the condensing and compacting member of the device under conditions of substantially uniform tension throughout the width of the sliver or roving.

5. In a mechanism for drawing textile sliver or roving for the manufacture of yarn, the combination of a pair of cooperating holding rolls receiving a strand of sliver or roving and through which it passes in a compressed flattened condition, a pair of rotatable pulling members in cooperating relationship and arranged to draft and attenuate the strand as well as to propel it forwardly and away from said holding rolls, and a device for condensing and compacting the fibers of the strand immediately before the fibers are gripped by and pass between the pulling members, and to control the movement to the compacting region of the fibers in that portion of the strand undergoing draft, said device being located between the holding rolls and the pulling members and comprising a fiber condensing and compacting member having a restricting discharge aperture, convex means arranged to spread and distribute the fibers of the moving strand laterally thereof and to guide the fibers to the condensing and compacting member, and convex means arranged to tension and guide the fibers of the moving strand to said convex fiber spreading and distributing means after the strand has passed away from the bite of the holding rolls in advancing to the pulling members.

6. In a mechanism for drawing textile sliver or roving for the manufacture of yarn, the combination of a pair of cooperating holding rolls receiving a strand of sliver or roving and through which it passes in a compressed flattened condition, a pair of rotatable pulling members in cooperating relationship and arranged to draft and attenuate the strand as well as to propel it forwardly and away from said holding rolls, and a device for condensing and compacting the fibers of the strand immediately before the fibers are

11

gripped by and pass between the pulling members, and to control the movement to the compacting region of the fibers in that portion of the strand undergoing draft, said device being located between the holding rolls and the pulling members and comprising a fiber condensing and compacting member having a restricting discharge aperture, convex means arranged to spread and distribute the fibers of the moving strand laterally thereof and to guide the fibers to the condensing and compacting member, and convex means arranged to tension and guide the fibers of the moving strand to said convex fiber spreading and distributing means after the strand has passed away from the bite of the holding rolls in advancing to the pulling members, said convex fiber condensing and distributing means and said convex fiber tensioning and guiding means being situated with respect to each other, said holding rolls, and said condensing and compacting member so as to alternately engage the top and bottom portions of the flattened strand passing thereover and to impart successive transverse displacements to said portions thereof in opposite directions for an amount such that the drawn fibers are caused to travel in longitudinal courses of equal length in passing from the holding rolls to the condensing and compacting member of the device.

7. In a mechanism for drawing textile sliver or roving, the combination of a pair of opposed rotatable holding rolls receiving a strand of sliver or roving and through which it passes in a compressed flattened form, a pair of opposed rotatable pulling members cooperating to provide a line of nip therebetween and arranged to draw the fibers whose front ends are gripped by the

12

pulling members and whose tail ends are subject to a retarding tension by adjacent other fibers held by the holding rolls, as well as to advance the strand under tension during the drawing operation, and a device for condensing and compacting the fibers of the strand and located in the drafting zone between said pairs of holding rolls and pulling members, said device comprising a base which includes an upturned fiber condensing and compacting member having a notched aperture the delivery end of which is positioned close to the line of nip of said pulling members, an intermediate elevated fiber expander member with a transverse ridge curved on a convex line for spreading and distributing the fibers of the strand laterally of its width as the moving strand passes over said ridge, and to guide the fibers to the condensing and compacting member, and a fiber tensioning arm member the underside of which is curved convexedly both longitudinally and transversely and arranged above and extending transversely of said base for tensioning and guiding the strand to said fiber expander member after the strand has passed the bite of the holding rolls in advancing to the pulling members.
